(57) **CLAIM**

The ornamental design for a game shaping device for outdoor sportsmen as shown and described.

DESCRIPTION

FIG. 1 is front, bottom, right perspective view of the game shaping device for outdoor sportsmen in a loading configuration.

FIG. 2 is a top side view of the embodiment shown in FIG. 1.

FIG. 3 is a bottom side view of the embodiment shown in FIG. 1.

FIG. 4 is a right side view of the embodiment shown in FIG. 1.

FIG. 5 is a left side view of the embodiment shown in FIG. 1.

FIG. 6 is a front side view of the embodiment shown in FIG. 1; and,

FIG. 7 is a rear side view of the embodiment shown in FIG. 1.

The broken lines shown are for the purpose of illustrating stitching that forms no part of the claimed design.

1 Claim, 5 Drawing Sheets
